UNITED STATES PATENT OFFICE

GLEN S. PIERCE AND EVERETT S. CHITTUM, OF COLUMBUS, OHIO, ASSIGNEES TO THE BUCKEYE STEEL CASTINGS COMPANY, OF COLUMBUS, OHIO, A CORPORATION OF OHIO

DEVICE FOR UTILIZING WASTE HEAT

Application filed November 15, 1928. Serial No. 319,577.

This invention relates to improvements in means for utilizing the waste heat of an industrial furnace such as an open hearth furnace, and it more particularly relates to an improved mechanism for operating the valve which diverts the heat and to improved means for installing the same in the furnace stack.

One of the objects of the invention is to provide a valve casing which can be readily installed in the stack at a point in close proximity to the takeoff conduit for the waste gases and which will act to support the upper part of the stack.

A further object of the invention is to provide improved operating mechanism for the valve of a nature which will permit the valve to be readily opened and closed.

Further objects of the invention will appear from the accompanying description and claims.

In the accompanying drawings:

Fig. 1 is a top plan view, partly in transverse section, showing our improved construction.

Fig. 2 is a partial section on the line 2—2 of Fig. 1.

Fig. 3 is an enlarged vertical section through one of the bearings of one of the 30 valve operating shafts.

Fig. 4 is a view partly in front elevation and partly in vertical section.

Fig. 5 is an enlarged fragmentary section on the line 5—5 of Fig. 2.

Fig. 6 is a section on the line 6—6 of Fig. 1.

Fig. 7 is an elevation on a reduced scale, showing a portion of a self-supporting stack in which our improved device is incorporated.

Fig. 8 is a section on the line 8—8 of Fig. 1, with some of the parts in a different working position from that shown in the other figures.

Figs. 9 and 10 are enlarged perspective views of details of the supporting track for the valve.

Referring to the drawings S' represents the upper portion and S'' the lower portion respectively of a furnace stack of the self-supporting type to which our improved valve

or damper mechanism has been applied. The lower portion S'' of the stack is suitably braced by members M at the bottom and is in the present case lined with a refractory material R. A takeoff conduit C is connected to this lower portion S'' for the purpose of carrying away the hot gases to a boiler (not shown) or other point where the heat may be utilized.

It has been the practice in some cases where the waste heat is taken from the stack to place a valve or damper in the top of the stack, such location however being objectionable for various reasons, one of which is that much heat is lost by convection or radiation and another being that the services of a steeple jack are frequently required to pack the valve and that the valve must necessarily be located a great distance from the operating mechanism. It is apparent therefore that the ideal point for the location of the valve or damper is immediately above the conduit C, as the loss of heat due to radiation or convection is minimized and the erection and maintenance of hazards incidental to stack-top dampers eliminated. It is also obvious that installation of the damper at a point adjacent the conduit C necessitates a construction of valve casing which is calculated to be supported by the lower portion of the stack and in turn support the upper portion of the stack.

The valve casing is formed of two parts 1 and 2 to provide a central valve chamber 3 and upper and lower aligned cylindrical extensions 4, which communicate with the chamber. In the event that this construction is applied to an existing stack, the two parts of the casing are placed around the stack at the desired point and bolted together by bolts 5' which pass through the flat-faced flanges or joints 5. Rivets are then driven through the stack and the extensions and that portion of the stack which passes through the chamber 3 cut away in any suitable manner such as by an oxygen torch. The removal of this comparatively narrow band from the stack results in separating the stack in two parts, the upper and lower portions S' and S'' previously re-

ferred to, the lower portion supporting the valve casing and the valve casing in turn supporting the upper portion.

The central valve chamber is in the nature of an enlargement, one-half thereof being semi-circular in shape and the other half having its outside dimensions of rectangular form, with one side of the rectangular shaped part formed open and provided with attaching flanges 6 for the purpose to be explained.

Each casing member and its extension are integrally formed and suitably braced by integral ribs 7 to provide a structure of sufficient strength to support the upper portion of the stack.

Inside and at the top of the lower stack portion S'' a valve seat member 10 is placed. The valve seat proper is indicated at 11, and is a comparatively narrow flat concentric seat, from which rise upwardly and angularly an outside wall 12 and an inside wall 13, the wall 13 being uniformly shaped while the wall 12 varies so as to present or effect a continuation at 12', the purpose of which will appear later. The seat member 10 is also provided with a downwardly extending flange 14 which serves to locate the member 10 concentrically within the stack portion S'', while around the lower slope of the wall 12 a fire-clay luting is employed, the lining R also being extended to the under side of the wall 13 to protect and seal the seat from the heat.

An annular valve 15 is provided, the diameter of which is approximately the mean diameter of the seat 11, there being an annular extension 16 which may rest directly on the seat 11, or which may embed itself in a sand seal, the walls 12 and 13, in connection with the seat 11, forming a trough adapted for this purpose. The under side of the valve 15 is provided with a plurality of ribs 17 having laterally extending flanges 17', the flanges 17' serving to retain in position the refractory lining 18 which is preferably packed into the spaces between the ribs 17.

The valve has a pair of diametrically opposite bosses 19 through which a shaft 20 is passed, which shaft has at each end a roller 21. In alignment with the rollers 21 are tracks 22, supported partly on the bottom of the chamber 3 and partly on a metal plate 23 which is secured to the lower flange 6 at the open end of the chamber and forms a continuation of the bottom of the chamber. The plate 23 is the bottom of a box-like housing into which the valve is withdrawn when it is desired to allow the gases to pass to atmosphere at the top of the stack S', the housing being preferable since it is desired that leakage of air into the stack is to be reduced as far as possible. The housing is formed of the bottom 23, sides 24, a removable top 25, and a removable end 26, with suitable stiffening girders and braces, such

as the extensions 24' of the sides 24, which are secured to the lower flange 6.

The valve is withdrawn or seated by a system of gearing. A shaft 28 is carried in bearings 29 secured to the sides 24, and has thereon a hand wheel 30, and a pinion 31. The pinion 31 meshes with a gear 32 on a shaft 33, carried in similar bearings 29. On the shaft 33 is a second pinion 34 meshing with a gear 35 on a shaft 36, on which are two pinions 37 with which are meshed rack-bars 38, resting on said pinions 37. The forward ends of the rack-bars have apertures through which are loosely passed the ends of the shaft 20. When the hand wheel 30 is turned there will be a forward or rearward movement, as the case may be, of the rack-bars 38, resulting in a movement of the valve 15. The initial opening movement of the valve 15 (from the position shown in Fig. 2) is a sliding movement along the seat 11, until the rollers 21 contact with the inclined ends 22' of the tracks 22, whereupon the valve is lifted bodily from the seat. When the rollers are on the tracks 22, the valve is pivotally suspended from the shaft 20, and provision is made to prevent the valve catching on any obstruction that may hinder its passage to the rear of the box structure (Fig. 8), the previously mentioned extended wall 12' serving to guide the valve, aided later by a beam 40, notched to accommodate the operating shafts 28, 33 and 36. Fixed to the sides 24 are a pair of angle plates 42, which support the rear ends of the rack-bars 38 when the valve is moved to open position. At various points around the chamber 3 are placed hand-hole openings 43 for the purpose of allowing renewal of the sand filling when desired.

In order to prevent substantial leakage of air into the stack through the housing and valve chamber the shaft bearings 29 are each provided with a solid bushing 44 which closely surrounds the shaft and said bearings are further provided with a flat flange 45 which is secured against the walls 24 and to the outside thereof, the cap 46 which secures the bushing 44 in place being also on the outside (Fig. 3). To each track 22 is fixed a removable bumper 47 which limits the rearward movement, the removability of which allows for easy assembling of the valve in the stack, although it is also possible to lower the valve into the box by removing the upper cover plate 25.

Having thus described our invention we claim:

1. In a mechanism of the character described, a chamber having a valve seat, a valve cooperating with said seat, a pair of stationary track rails for said valve each having an inclined portion adjacent said seat, a pair of racks pivotally connected directly

with said valve, and means for reciprocating said racks.

2. In a mechanism of the character described, a chamber having a valve seat, a valve cooperating with said seat, a pair of stationary track rails for said valve each having an inclined portion adjacent said seat, a pair of racks pivotally connected directly with said valve, and means for reciprocating said racks, said means comprising a shaft; pinions connected with said shaft and meshed with said racks, an operating shaft, and gearing between the two shafts.

3. In a mechanism of the character described, a chamber having a valve seat, a valve cooperating with said seat, a pair of anti-friction rolls carried by said valve, a pair of stationary track rails for said valve cooperating with said rolls and each having an inclined portion adjacent said seat, a pair of racks pivotally connected directly with said valve, and means for reciprocating said racks.

4. In a mechanism of the character described, a chamber having a horizontally arranged annular valve seat, a horizontal disk-shaped valve cooperating with said seat, one side of said chamber being open, a housing connected with the open side of said chamber and communicating therewith, a pair of racks pivotally connected directly with said valve, a pair of track rails leading from said seat into said housing each having an inclined portion adjacent said seat, operating mechanism supported in said housing including pinions meshed with said racks, supports in said housing for said racks, and means in said housing for supporting said valve.

5. In a valve mechanism adapted to be inserted in a furnace stack formed of two spaced-apart sections, the combination of a structure for connecting the stack sections and supporting the upper stack section comprising a valve chamber and upper and lower cylindrical extensions to receive adjacent ends of the stack sections rigidly connected with the chamber, a movable valve in said chamber, and means carried by said structure for operating said valve.

6. In a valve mechanism adapted to be inserted in a furnace stack formed of two spaced-apart sections, the combination of a sectional structure for connecting the stack sections and supporting the upper stack section comprising a valve chamber and upper and lower cylindrical extensions to receive adjacent ends of the stack sections rigidly connected with the chamber, means for clamping the parts of said structure together and thereby clamp the cylindrical extensions to the stack sections, a movable valve in said chamber, and means carried by said structure for operating said valve.

7. In a valve mechanism adapted to be inserted in a furnace stack formed of two

spaced-apart sections, the combination of a two-part structure for connecting the stack sections and supporting the upper stack section comprising a valve chamber and upper and lower cylindrical extensions to receive adjacent ends of the stack sections, means for clamping the parts of said structure together to thereby clamp the extensions about the stack sections, a movable valve in said chamber, a housing connected to and communicating with said valve chamber, and means carried by said structure and encased in said housing and chamber for operating said valve.

8. In a valve mechanism adapted to be inserted in a furnace stack formed of two spaced-apart sections, the combination of a sectional structure for connecting the stack sections and supporting the upper stack section comprising a valve chamber and upper and lower cylindrical extensions rigidly connected with said chamber to receive the adjacent ends of the stack sections, means for clamping the parts of said structure together to thereby cause the extensions to clamp the stack sections, that portion of the structure forming the valve chamber having an opening of rectangular form, a housing secured about the walls of said opening, a valve seat in said chamber which surrounds the upper end of the lower stack section, a valve cooperating with said seat, and means located in said chamber and housing for moving said valve to and from its seat.

In testimony whereof, we have hereunto set our hands this 25th day of October, 1928.

GLEN S. PIERCE.
EVERETT S. CHITTUM.
